UNITED STATES PATENT OFFICE.

OSSIAN G. LYON, OF AKRON, OHIO, ASSIGNOR TO RAYON RUBBER CO., OF RAVENNA,
OHIO, A CORPORATION OF OHIO.

DESIGN FOR A HEEL FOR A BOOT, SHOE, OR SIMILAR ARTICLE.

54,938.

Specification for Design.

Patented Apr. 20, 1920.

Application filed October 17, 1919. Serial No. 331,481. Term of patent 14 years.

To all whom it may concern:

Be it known that I, OSSIAN G. LYON, a citizen of the United States of America, residing at Akron, in the county of Summit and State of Ohio, have invented a new, original, and ornamental Design for a Heel for a Boot, Shoe, or Similar Article, of which the following is a specification, ref-

erence being had to the accompanying drawing, forming part thereof.

The figure is a view in perspective of a boot and shoe heel, showing my new design.

I claim:

The ornamental design for a heel for a boot, shoe, or similar article, as shown.

OSSIAN G. LYON.
